UNITED STATES PATENT OFFICE.

YUSUKE TAMAMURA, OF ASHIO, JAPAN.

HOISTING AND CONVEYING APPARATUS.

SPECIFICATION forming part of Letters Patent No. 770,545, dated September 20, 1904.

Application filed May 18, 1903. Serial No. 157,517. (No model.)

To all whom it may concern:

Be it known that I, YUSUKE TAMAMURA, a subject of the Emperor of Japan, and a resident of Ashio, in the Province of Shimozu, 5 Japan, have invented a new and useful Improvement in Hoisting and Conveying Apparatus, of which the following is a specification.

In the accompanying drawings, Figure 1 is a side view of an apparatus containing my invention. Fig. 2 is a side view of the load-carriage. Fig. 3 is an end view of the load-carriage. Fig. 4 is a vertical transverse section of the load-carriage. Fig. 5 is a vertical longitudinal section of the load-carriage. Fig. 15 6 is a horizontal section of the load-carriage on the line xx of Fig. 5. Fig. 7 is a longitudinal section on the line yy of Fig. 5. Fig. 8 is a modification. Fig. 9 is the load-carriage of the modification.

20 A B are the head and tail supports of a trackway C, upon which the load-carriage D travels.

E is the load, and F the fall-block.

25 G is a rope-actuator, which in the form shown consists of the two drums g g' , operatively connected to move in unison by being fixed on the same driven shaft g'' .

H is a counter-actuator, which in the form shown consists of the counterweights h h' 30 and the rest h'' .

I is the operating-rope, which in the form shown consists of the run i from the drum g to the head-support sheave 1, the runs i' to and from the counterweight-sheave 2, the run i'' 35 to the tail-support sheave 3, the run i''' to the tail-sheave 4, the run i''' to the tail-support sheave 5, the run i'''' to the load-carriage sheave 6, the run i''''' to the fall-block sheave 7, the run i'''''' to the load-carriage sheave 8, 40 the run i''''''' to the head-support sheave 9, the runs i''''''' to and from the counterweight-sheave 10, and the run i'''''''' to the drum g' . The rope I is coiled inversely on the drums g g' , so that by movement of the actuator G in either direction one drum pays out the rope as the other hauls it in. Detaining mechanism, the preferable form of which is hereinafter described, is provided whereby the travel of the rope-runs i'' and i''' over their supporting-sheaves 6 and 8, respectively, is alternately

prevented and permitted. When the travel of both the runs i'' and i''' is prevented, the actuator G will move the load-carriage D back and forth along the trackway C, the length of the fall-loop i'' i''' remaining constant and the counterweights h and h' being stationary upon the rest h'' . When the travel of the run i''' is prevented, but of i'' permitted, as shown in Fig. 1, the movement of the actuator G will shorten or lengthen the fall-loop and raise or lower the fall-block, the load-carriage D remaining stationary and the counterweight h also remaining stationary on the rest h'' , but the counterweight h' being lowered or raised inversely to the fall-block. When the travel of the run i'' is prevented, but of i''' permitted, the movement of the actuator G will shorten or lengthen the fall-loop and raise or lower the fall-block, the load-carriage remaining stationary and the counterweight h' also remaining stationary on the rest h'' , but the counterweight h being lowered or raised inversely to the fall-block. Hence by locating the two points at which the travel of the rope I over the sheaves 6 and 8, respectively, shall be detained the operator of the actuator G may control the raising or lowering of the fall-block or the conveying of the same by the movement of the carriage along the trackway.

For adjusting the position or taking up the slack of the rope I a means of adjustment 47 may be connected with the block of the tail-sheave, and the two drums g and g' may be inversely adjustable relatively to each other.

The carriage-frame, by which the sheaves 6 and 8 are supported, consists of the side plates 11 12, rigidly connected together and rigidly suspended by the hanger 13 from a truck-frame 14, pivotally supported by the trucks 15 and 16 on the wheels 17 18 19 20.

j j' are two projections or enlargements formed in or upon the rope, each of which preferably consists of two members 21 and 22, attached, respectively, to the adjacent ends of rope and connected together by a universal joint 23.

The detaining mechanism preferably consists of two detaining members k and k' , which are alike in construction, but which are mount-

ed, respectively, concentric with the sheaves 6 and 8, facing each other. They are so mounted as to be capable of oscillation between the positions occupied by k in Figs. 2 and 5, respectively. Each of these detaining members consists of the two side plates 24 and 25 on opposite sides of the sheave rigidly secured together beyond the periphery of the sheave and each carrying the forked projections 26 and 27 in such position that the opening between the forks of each projection oscillates in the plane of the sheave, and consequently of the rope I. The distance between the two forks of each of the projections 26 and 27 is sufficient to freely receive the rope, but not to permit of the passage of the rope projection j or j' . The rope is constantly held in the fork of the projection 27 by the cross-piece 28 between the extremities thereof; but, there being no connection between the extremities of the forked projection 26 and it being shorter than the forked projection 27, it oscillates freely into and out of engagement with the rope. Each detaining member k and k' carries a projection 29, which coöperates with latching and unlatching mechanism, hereinafter described, so that when latched the detaining member is held in the position of k' , Fig. 2, where the rope projection j' is detained between the forked projections 26 and 27; but when unlatched the detaining member drops into the position of k , Fig. 2, when the rope projection j is released. The movement of the detaining member from the unlatched to the latched position is performed by the rope projection itself striking against the forked projection 27 and oscillating the detaining member to such a position that the latching mechanism engages the projection 29.

The latching and unlatching mechanism in its preferred form may be described as follows: l l' are two dogs respectively pivoted to the frame at 30 and 31. Each of these dogs contains an inclined deflecting-head 32, an inwardly-facing hook 33, an outwardly-facing hook 34, and a hump 35 between said hooks. Said dogs l l' are held in position by the levers m m' , both of which are fulcrumed upon the same pin 36, upon which the pawls n and n' are pivoted. Each of the levers m and m' makes at its upper end a pin 37 and slot 38 connection with one of said dogs, and the upper arms of said levers are held together by the spring 39, the tendency of which is to hold the said levers at the inner ends of said slots, and therefore maintain the dogs l and l' in the horizontal position shown in Fig. 5, though each of said dogs is free to be moved downward in antagonism to said spring, either by a downward pressure upon the dog itself or an upward pressure on the lower arm of its lever. The lower arm of each of the levers m and m' extends under that pawl which is opposite the dog with which the lever is

connected, so that whenever one of the dogs is depressed the opposite pawl will be raised into unlatching position, (see dog l and pawl n of Fig. 2,) while whenever the dog is in horizontal position the pawl opposite to it will be in latching position. (See dog l and pawl n' , Fig. 2.) Upon the lower or rear end of each lever m and m' is fixed a finger o and o' , which respectively project into the path of oscillation of the pins 40 and 41, mounted, respectively, upon the detaining members k and k' . When the load is lifted and the counter-weight lowered to its rest, the rope will pull the carriage until the roller is transferred from hook 34 to hook 33 of the dog. The pin 40 moving upward will raise the finger o , so as to depress the dog l and permit the roller to escape from the hook 33, so that the rope can continue pulling the carriage along the trackway until the dog l encounters the roller on the other hanger, p .

p and p' are hangers, each of which is secured on the under side of the trackway by the clips 42 and 43 and each of which supports at its lower extremity a horizontal transverse convex roller 44 and also the downwardly-extending diverging weighted arms 45 and 46, which tend to hold the hangers in proper position. As the load-carriage travels along the trackway the rollers 44 are thus held in the paths of the dog-heads 32.

The operation of the detaining latching and unlatching mechanisms may be described as follows: When the carriage is conveying the load along the trackway, the parts are in the position shown in Fig. 5, where the two rope projections j and j' are both held by the detaining devices, which are in turn held by the pawls n and n' , both counterweights being supported on the rest. When one of the dog-heads collides with one of the rollers 44, the dog is depressed, admitting the roller into its hook 33 and over its hump 35 and into its hook 34, being the position shown at the left of Fig. 2. This depression of the dog causes the rear end of its lever to raise the opposite pawl into unlatching position and permit the detaining member to drop into the position shown at the right of Fig. 2, setting free one of the rope projections, as j , the other rope projection still remaining detained by its detaining member. This condition will continue until the fall-block has descended and ascended, whereupon the rope projection j by contact with the arm 27 will raise the detaining member k to and beyond its first or latching position until the pin 40 has depressed the dog below engaging position with the roller 44, whereupon the carriage will start along the trackway. Then the detaining member k will drop back until the pawl falls behind the projection 29, as shown in Fig. 5. This is the carrying position, the weight of the load being supported upon the detaining members and the counter-

weights upon the rest, so that the actuator is only called upon to propel the carriage. Each counterweight should be heavy enough to overbalance the load.

5 In the modification shown in Figs. 8 and 9 the rope i^1 extends from the actuator G and sheave 56 at the head to the tail-sheave 50, thence around the sheave 51 of the block from which the counterweight h^2 is suspended; 10 thence back to the load-carriage frame, where its end is made fast at 52. The rope i^2 extends from the opposite side of the actuator G over the head-sheave 57 and carriage-sheave 53 under the fall-block sheave 54 and 15 has its end made fast to the load-carriage frame at 55. It contains the projection or enlargement j^2 , and the load-carriage contains the detaining member k^2 for co-operating with the dog l^2 and hanger p^2 and pawl n^2 , 20 in the manner already described in connection with the form first described, through the arm o^2 and projection 61. A hook 59 on the hanger 60 acts as a stop for the stud 58 on the detaining member k^2 to limit the downward movement thereof.

It will be observed that the apparatus shown in Fig. 1 is double-acting, having two hoisting and lowering stations P and P' , while the apparatus shown in Fig. 8 is single-acting, its hoisting and lowering station being at P^2 . In both the double and single acting constructions the carriage traction-rope which draws the carriage toward a station remains fixed to the carriage, while the other rope in 30 performing the lowering and hoisting has a running engagement with the carriage. In the single-acting construction the same rope may always give this traction and may therefore be permanently fixed to the carriage, as 35 in Fig. 8; but in the double-acting construction each rope is called upon to give the traction toward one station and the lowering and hoisting at the other station. In other words, in the single-acting construction one run of 40 the looped fall-rope may be permanently fixed to the carriage, while in the double-acting construction each run is disconnected at the station at which it is called upon to do the lowering and hoisting. Therefore in the double-acting the 45 fixing of each rope to the carriage is temporary. I use the term "fixed to the carriage" to include, broadly, both constructions, whether the fixing be permanent or temporary, and I use the term "carriage traction-rope" to include, broadly, both constructions, whether the rope act permanently as 50 the traction-rope or only temporarily toward one of two stations, and I also use the term "hoisting-rope" broadly to cover both constructions, whether the same rope always or 55 the two ropes alternately act as the hoisting-rope. In both the single and double acting constructions the counter actuator or weight of the carriage traction-rope is in action when 60 the carriage is stopped and the lowering and

hoisting is being performed by the other rope, and through the operative connection between the primary actuators of the two ropes (whether this connection be made by the use of a single drum, as in Fig. 8, or two connected 70 drums, as in Fig. 1, or by any other suitable connection) the counter actuator or weight has a reciprocal connection with the load, whereby it assists the primary actuator in hoisting the load. In other words, the two 75 ends of the rope are so connected by the actuator as to form substantially an endless rope through which the counter-actuator assists the actuator in handling the load. The runs of the traction-rope between the sheaves 50 and 80 51 of the single-acting construction and the corresponding runs in the (for the time being) traction-rope of the double-acting construction furnish a rope reserve permitting the prime actuator mechanism to continue running after the traction-rope has pulled the carriage to the station.

Although the double and single acting constructions contain the above and other generic features in common, they nevertheless severally contain other very important features of invention. For example, when constructed in the preferred form shown the double-acting apparatus enables a load to be hoisted at one station and conveyed to and lowered at another station by the use of only two ropes extending from the prime actuator mechanism to the carriage, the rope which acts as the traction-rope toward one station acting as the hoisting and lowering rope at the other station, and vice versa. Moreover, the hoisting at one station and the conveying to and lowering at the other station may all be done without stopping or reversing the actuation of the two ropes by the prime actuator. In other 95 words, when the prime actuators g g' are started to hoist the load at one station they need be neither stopped nor reversed till the load has been conveyed to and lowered at the other station.

Having thus described my invention, I claim as new and desire to secure by Letters Patent—

1. In combination, a rope-support, a rope having a fall pendent from the same, means whereby the running of the rope on opposite sides of the fall is detained and released, mechanism for actuating the rope in both directions and a counter-actuator operating upon said rope on each side of said fall.

2. In combination, an actuator, a rope leaving and returning to said actuator and forming four loops, counter-actuators in two of said loops, a fall-block in a third loop, a tail-guide in a fourth loop, guides whereby said fall-block loop is supported and mechanism 125 whereby said rope is detained and released on opposite sides of said fall-block.

3. In combination, a trackway, a carriage thereon, a rope having a fall pendent from said carriage, means whereby said rope is ac- 130

- 5 tuated in both directions, two projections fixed to the rope and means mounted on the carriage whereby said projections are alternately detained on opposite sides of the fall.
- 5 4. In combination, a trackway, a carriage thereon, a rope having a fall pendent from said carriage, means whereby said rope is actuated in both directions, two projections from said rope and means whereby the same are 10 respectively detained on opposite sides of the fall.
- 5 5. In combination, a trackway, a carriage thereon, a rope having a fall pendent from said carriage, means whereby said rope is actuated in both directions, a counter-actuator 15 acting on said rope on each side of said fall and means whereby said rope is detained and released between each counter-actuator and said fall.
- 20 6. In a hoisting and conveying apparatus containing a trackway, a carriage, a looped fall and an actuator, in combination with said parts, mechanism mounted on the carriage laying hold of both branches of said loop whereby the actuator is relieved of the weight of 25 the load during the conveying, and means whereby either branch of said loop is released while the other is held during the hoisting and lowering.
- 30 7. In a load-carriage for a hoisting and conveying apparatus, in combination, a pair of reciprocating dogs, a pair of reciprocating fall-rope-holding members each adapted to be operated by a projection on the fall-rope and 35 means whereby the reciprocation of each of said members is communicated to one of said dogs.
8. In a load-carriage for a hoisting and conveying apparatus, a pair of reciprocating dogs, 40 a pair of reciprocating fall-rope-holding members, pawls whereby both of said members are held and mechanism whereby the reciprocation of each of said dogs is communicated to one of said pawls.
- 45 9. In combination, a trackway, two trips located respectively at the load-hoisting and load-lowering points thereof, two members on the carriage jointly supporting the load between said tripping-points and mechanism 50 on the carriage through which each of said trips operates to release the load from one of said supporting members.
10. In combination, a trackway, a carriage thereon, an actuator, rope-runs extending 55 from the actuator to the tail and back to the carriage and from the actuator to the carriage, a counter-actuator operating on one of said runs and means mounted on the carriage whereby the running of the other of said runs 60 is detained and released.
11. In combination, a carriage, two actuated runs of rope extending thereto and forming a fall, means for fixing each of said runs to the carriage, means whereby one of said ropes 65 is detached from the carriage to lower or hoist the load and an actuator whereby said ropes are actuated inversely while the load is being lowered or hoisted.
12. In a conveying apparatus having two hoisting or lowering stations, in combination, 70 a carriage moving between said stations, two actuated ropes extending to said carriage, means whereby both said ropes are fixed to the carriage when moving between stations, and means whereby one rope is detached from 75 the carriage at each station to lower or hoist the load.
13. In a conveying apparatus having two hoisting or lowering stations, in combination, 80 a carriage moving between said stations, a looped fall pendent from said carriage, means for actuating both runs of said loop, means whereby both runs are fixed to the carriage while moving between stations and means for detaching one run from the carriage at each 85 station to permit said run to hoist or lower the load.
14. In a conveying apparatus having two hoisting or lowering stations, in combination, 90 a carriage traveling between the same, a fall-rope, two projections fixed thereon, means whereby said projections may be fixed to the carriage and means whereby one of said projections is detached from the carriage at each of said stations.
15. In combination, a trackway having two hoisting or lowering stations, a carriage traveling between the same, a fall-rope, two projections fixed thereon, means whereby both of said projections are fixed to the carriage 100 while traveling between stations and means whereby one of said projections is detached from the carriage at each of said stations.
16. In a hoisting and conveying apparatus, in combination, a carriage, two ropes extending thereto, a trackway containing two stations, means whereby each rope forms a traction engagement with said carriage toward one of said stations, and means whereby one of said ropes forms a running engagement 110 with said carriage at each of said stations.
17. In combination, a carriage, an actuator, a trackway, two stops, two ropes each containing a rope reserve permitting the actuator to continue to lower the load after the carriage has reached either stop and means whereby one of said ropes forms a fixed engagement and the other a running engagement with said carriage at each of said stops.
18. In a hoisting apparatus, in combination, 120 a carriage, a carriage-traction rope containing a rope reserve, a hoisting-rope, a holder opposing the tendency of the hoisting-rope to move the carriage and means whereby said holder is released by the ascent of the fall.
19. In a hoisting apparatus, in combination, 125 a carriage, a carriage-traction rope containing a rope reserve, a hoisting-rope, a holder opposing the tendency of the hoisting-rope to move the carriage and means whereby said 130

holder is released by the travel of the hoisting-rope.

20. In a hoisting apparatus, in combination, a carriage, a carriage-traction rope containing a rope reserve, a counterweight suspended by said rope reserve, a hoisting-rope, a holder opposing the tendency of the hoisting-rope to move the carriage and means whereby said holder is released by the ascent of the fall.

21. In a hoisting apparatus, in combination, a carriage, a carriage-traction rope containing a rope reserve, a hoisting-rope also containing a rope reserve, a holder opposing the tendency of the hoisting-rope to move the carriage and means whereby said holder is released by the ascent of the fall.

22. In a hoisting apparatus, in combination, a carriage, a carriage-traction rope containing a rope reserve, a hoisting-rope also containing a rope reserve, a counterweight suspended by each of said rope reserves, a holder opposing the tendency of the hoisting-rope to move the carriage and means whereby said holder is released by the ascent of the fall.

23. In a hoisting apparatus, in combination, a carriage, a carriage-traction rope containing a rope reserve, a hoisting-rope, a holder one member of which is mounted upon the carriage opposing the tendency of the hoisting-rope to move the carriage and means whereby said holding member is released by the ascent of the fall.

24. In a hoisting apparatus, in combination, a carriage, a carriage-traction rope containing a rope reserve, a hoisting-rope, a holder consisting of a member having a fixed support and a member mounted upon the carriage opposing the tendency of the hoisting-rope to move the carriage and means whereby said holder is released by the ascent of the fall.

25. In a hoisting apparatus, in combination, a carriage, a carriage-traction rope containing a rope reserve, a counterweight suspended by said rope reserve, a hoisting-rope, a holder opposing the tendency of the hoisting-rope to move the carriage, means whereby said holder is released by the ascent of the fall and a rest supporting said counterweight upon the release of said holder.

26. In a hoisting apparatus, in combination, a carriage, a carriage-traction rope containing a rope reserve, a hoisting-rope, a holder opposing the tendency of the hoisting-rope to move the carriage, means whereby said holder is released by the ascent of the fall and a connection between said ropes at the actuator.

27. In a hoisting apparatus, in combination, a carriage, a carriage-traction rope containing a rope reserve, a hoisting-rope, a projection fixed to said hoisting-rope, a holder opposing the tendency of the hoisting-rope to move the carriage and means whereby said holder is released by said projection.

28. In combination, a trackway, a carriage

thereon, a rope extending from the head to the carriage, a rope extending from the head toward the tail and back to the carriage, a rope reserve in one of said ropes, a traction engagement between one of said ropes and the carriage, a running engagement between the other of said ropes and the carriage, an actuator operating said ropes inversely, a holder opposing the travel of the carriage and means operated by the travel of one of said ropes whereby said holder is released.

29. In combination, a carriage, a trackway, a substantially endless rope forming a looped fall from the carriage and containing a rope reserve, means whereby said rope is fixed to the carriage at one side of the fall and forms a running engagement on the other side of the fall, an actuator whereby said rope is run in both directions, a holder opposed to the travel of said carriage and means operated by the movement of one of said parts whereby said holder is released.

30. In combination, a trackway, an actuator, a carriage on said trackway, a rope extending from said actuator to and through said carriage and thence back to the actuator and having a fall pendent from said carriage, means mounted on the carriage whereby the running of the rope on opposite sides of the fall is alternately detained whereby the raising or lowering of the load is performed by the rope on the undetained side of said fall.

31. In a hoisting apparatus, in combination, a trackway, hoisting mechanism at the end thereof, a carriage thereon, rope-runs extending from said mechanism to opposite ends of the carriage and forming a traction engagement with and a fall below the carriage, a holder opposing the movement of the carriage during the descent and ascent of the fall, a counter-actuator operating during the ascent and descent and means whereby said holder is released by the ascent of the fall.

32. In a hoisting apparatus, in combination, a trackway, hoisting mechanism at the end thereof, a carriage thereon, rope-runs extending from said mechanism to opposite ends of the carriage and forming a traction engagement with and a fall below the carriage, a projection on said fall, a holder opposing the movement of said carriage by the fall-rope, mechanism whereby said holder is released by said projection and a rope reserve in the rope-run forming the traction engagement with the said carriage.

33. In combination, a carriage, a carriage traction-rope, a hoisting-rope, a projection fixed thereon, means whereby said projection is held by the carriage while traveling, means whereby said projection is cast off at the end of the carriage travel, a holder for the carriage while said projection is cast off, means whereby said holder is released upon the return of said projection and a counter-actuator

acting upon said traction-rope during the movement of said projection to or from the carriage.

34. In combination, a trackway, a carriage, a hoisting-rope extending to the carriage and containing a looped fall therefrom, means whereby the runs of the loop may be actuated inversely, means whereby each run is fixed to the carriage and means whereby one only of said runs is automatically detached from the carriage to lower or hoist the load.

35. In a hoisting apparatus, in combination, a trackway, a carriage, two holders respectively opposing the movement of the carriage in opposite directions, a hoisting-rope containing a looped fall from said carriage, two projections on said fall, and mechanism where-

by one of said holders is released by each of said projections.

36. In a hoisting apparatus, in combination, a carriage, a trackway, a rope forming a looped fall from the carriage and extending toward each end of the trackway and containing a rope reserve, two holders respectively opposing the movement of the carriage in opposite directions and means whereby each of said holders is released.

In testimony whereof I have hereunto signed my name in the presence of two subscribing witnesses.

YUSUKE TAMAMURA.
